Patented Aug. 9, 1898.

L. B. ALLEN.

ILLUMINATING APPARATUS.

(Application filed Feb. 3, 1896.)

(No Model.)

UNITED STATES PATENT OFFICE.

LESLIE B. ALLEN, OF SPRINGFIELD, MASSACHUSETTS.

ILLUMINATING APPARATUS.

SPECIFICATION forming part of Letters Patent No. 608,745, dated August 9, 1898.

Application filed February 3, 1896. Serial No. 577,955. (No model.)

To all whom it may concern:

Be it known that I, LESLIE B. ALLEN, a citizen of the United States, and a resident of Springfield, Hampden county, Massachusetts, 5 have invented certain new and useful Improvements in Illuminating Apparatus, of which the following is a specification:

This invention relates to improvements in that class of illuminating systems in which 10 hydrocarbon is used, the same being provided in a service-tank and automatically fed to the lamp or lamps as required to replenish them as the oil therein is consumed in burning.

In the class of apparatus to which this invention pertains the principal difficulty has 15 been found to consist in the accumulations of air in the pipe which feeds the lamps with oil, which prevents the perfect operation of siphonage after the lamps have been run 20 awhile. Various expedients have been devised for overcoming the effects of the air accumulations, some of which have been put into use with fairly good results. Still the objection of complexity, cumbrousness, and 25 expensiveness has always existed, and therefore it is the purpose of the present invention to provide a lamp-supplying system or apparatus which shall be most simple, inexpensive, and easy of establishment and operation 30 and one in which only the simplest and most common instrumentalities are employed; and to this end the invention consists in the constructions, arrangements, and combinations of parts with respect to their co-operative effects, all substantially as will hereinafter 35 fully appear, and be set forth in the claims.

Reference is to be had to the accompanying drawings, in which the present improvements are illustrated, Figure 1 being an elevation 40 with parts in section, showing the lamp system as arranged for successful operation. Fig. 2 is a sectional view of parts located in the service-tank on a large scale. Fig. 3 is a horizontal section on line 3-3, Fig. 2. Fig. 4 is a plan view of an improved adjustable bracket or fixture which may be advantageously used in conjunction with the present improvements. Figs. 5 and 6 are front and edge views of said fixture. Fig. 7 is a view 45 in elevation and vertical somewhat similar

to Fig. 1, but showing a reversal in the arrangement of the pump, which, however, as will be perceived hereinafter, is no departure from this invention. Fig. 8 is a vertical sectional view, on a large scale, showing a valve 55 applied in the telescopic portion of the branch which conveys the oil to the lamp or lamps.

Similar characters of reference indicate corresponding parts in all the views.

In the drawings, A represents the service- 60 tank, which is supported suitably at about the level at which the lamp is desired. In practice a large number of lamps are comprised in the system; but it is not here necessary to illustrate or refer to them in plurality further than may be incidentally done.

B represents a pump located in the service- 65 tank, and this pump has connected therewith the feed-pipe C, which leads upwardly to or near the ceiling, and thence has a course horizontally, returning in the return member C² and depending branch C³ of service-tank, the end of this branch C³ being necessarily submerged in the oil in said tank. The feed-pipe 70 has the depending branch D, over which telescopes the pipe F, which at the outer end has the branch or member F² horizontally supported, on which the lamp or lamps G are mounted. The portion of the feed-pipe C which is submerged in the oil in the service- 75 tank has an inlet-port a, through which to take oil directly from the said tank. This port a has applied thereto a cock or equivalent device (indicated at b) for closing it. In Figs. 1, 2, and 3 this closing device is indicated as a 80 sleeve 10, which fits over the pipe C closely and which has the perforation 12 therein, which may by the turning of the sleeve be either placed to register with said port a or turned out of registry therewith to close the port. 85 The sleeve has the radial projection 13, whereby by the use of a rod or other implement to turn the sleeve.

The oil-level in the lamps is to be automatically maintained at the same level as the 90 top of the oil in the service-tank A, and this is done on the well-known siphon principle, for with the feed-pipe full of oil, as also the telescopic branch leading to the lamps, so soon as the oil in the lamp-founts falls below 95 100

the normal oil-level (indicated by the dotted lines at x) the lamp branch becomes the long leg of the siphon, whereupon the replenishment is effected. Tank H is a supply-reservoir and tank J is an overflow-receptacle to which pipe d leads from an upper portion of the service-tank A. Under a well-known principle the oil in tank A is maintained up to the normal level automatically as supplied 10 from the closed tank H. The horizontal portion C^2 of the return-pipe is preferably just above the horizontal portion of the feed-pipe C. Hence the accumulations of air will naturally ascend into said upper portion.

15 At intervals, as indicated at y , pipe connections may be made between the horizontal portion of the feed-pipe and the portion C^2 of the return-pipe thereabove for facilitating the aforementioned clearance of the air. Where 20 the telescopic vertical tube F joins the horizontal tubular member on which the lamp-fount is carried a valve (indicated at w) is applied, which when the telescopic member is up to the position for maintaining the lamps 25 at the oil-level x is held open, (see Fig. 8,) but which when the telescopic tube member is lowered closes the oil-passage through the depending branch D and prevents the same from flowing to the lamps to run the latter 30 over. No novelty is believed to exist in this description of valve; but its provision or the provision of an equivalent device is very desirable in this apparatus to render it safe and practical.

35 Now with respect to Fig. 1 of the drawings, to place the apparatus in condition for lighting, the oil being in the service-tank up to the normal level, the telescopic member F is lowered, whereby the lower end of depending 40 branch D is closed. The port a in the feed-pipe below the oil is closed, and the pump B is operated, filling the continuous pipe C C^2 C^3 and the depending branch D. The port a is then opened, the telescopic pipe F and lamps 45 raised, opening the valve at w , whereupon the lamp-founts fill with oil up to the level of oil in tank A, and the illumination may be assured.

Now, again, to rid the undue accumulation 50 of air in the pipes C C^2 C^3 the same operations are repeated—lamps lowered, port a closed, and the pump operated—whereupon the circulation of solid oil through the pipes will drive the air down pipe member C^3 into 55 the service-tank, up from the bottom of which it will bubble and escape to the atmospheric air. In Fig. 7 substantially the same idea of means is employed, there being a reversal in the application and mode of operating the 60 pump B^2 , which here is understood as being a suction-pump. Here the suction-pump is applied at the end of the return member of the feed-pipe, the outgoing member of the feed-pipe merely requiring to be submerged 65 in the oil and not requiring an opening-and-

closing cock or port therein. The siphon effect is had between the lamp G and the vertical portion of the feed-pipe C by way of the depending branch D and horizontal portion of the feed-pipe, as before, and the 70 pump never becomes a factor in the operation of the apparatus except preparatory to establishing the conditions for illumination and once in several weeks, when the air clearance is to be effected. In Fig. 7 a wall-bracket is shown, on which the depending telescopic pipe-section F and the horizontal arm F^3 , which forwardly supports the lamp away from the wall, is adjustably mounted. 75 This bracket M consists of the wall-plate f , through which are screws to secure it to the wall, the forwardly-standing vertical dovetail rib g , the shelf-like part h , which is horizontal and which has the depending member h^2 , which embraces and may slide on said dovetail rib, and the confining-screw j .

When it is required to lower the lamps for the purpose before referred to, by loosening the set-screw the movable part of the bracket slides downwardly, carrying with it the telescopic tube F and branch and lamp thereon, and the set-screw may be temporarily tightened again to hold the movable parts as lowered.

I claim—

1. In a lighting system, the oil-service tank, a lamp, an oil-feed pipe running continuously from the tank upwardly, then horizontally over and beyond the lamp, having a return-bend and a continuation therefrom back to 100 and terminating within the tank, a depending branch pipe, between the said return-bend and the tank, which connects the feed-pipe with the lamp, and a pump connected to the feed-pipe for causing at pleasure a flow of oil 105 from the tank through said feed-pipe back to the tank for expelling air accumulations in said pipe, the oil for the lamp being taken directly from the oil-service tank through the pipes C, C', D, substantially as described. 110

2. In a lighting system, the oil-service tank, a lamp, an oil-feed pipe running continuously from the tank upwardly, then horizontally over and beyond the lamp, having a return-bend and a continuation therefrom back to 115 and terminating within the tank, a depending branch pipe between the said return-bend and the tank which connects the feed-pipe with the lamp, and provided with a valve for cutting off the connection between the feed-pipe and lamp, and a pump connected to the feed-pipe for causing a flow of oil from the tank through said feed-pipe back to the tank, for expelling air accumulations in said pipe, the oil for the lamps being taken directly from 120 the oil-service tank through the pipes C, C', D, for the purpose set forth.

3. In an oil-supplying device, in combination an oil-tank, an oil-fount, a siphon adapted to carry oil by siphonic action from said tank 130

to said fount, a pump adapted to create a flow of oil through said siphon, and an oil-carrying return-pipe connecting the outer end of the substantially horizontal portion of said siphon 5 beyond its outer leg with said tank, substantially as described.

In testimony that I claim the foregoing as

my invention I have signed my name, in presence of two witnesses, this 28th day of January, 1896.

LESLIE B. ALLEN.
